FIG. 2

UNITED STATES PATENT OFFICE

2,468,273

AUTOMATIC TRANSMITTER

Louis M. Potts, deceased, late of Evanston, Ill., by
 Martha W. C. Potts, executrix, Evanston, Ill.,
 assignor to Teletype Corporation, Chicago, Ill.,
 a corporation of Delaware

Application March 21, 1947, Serial No. 736,329

4 Claims. (Cl. 178—17)

1

This invention relates to telegraph tape transmitters and particularly to means for automatically feeding a succeeding message tape into transmitting position when a prior message tape has completed transmission of its message.

The present invention is concerned with an automatic tape placement device for tape transmitters which functions to automatically feed a succeeding message tape into transmitting position after a prior message tape has completed transmission of its message. Such an arrangement is especially adapted for use at a central office exchange whereat an attendant who is taking care of a series of transmitters may keep the individual transmitters continuously supplied with tape messages without waiting for the end of a message being currently transmitted. While a particular transmitter is functioning to send message signals, the attendant may insert the leading end of a new tape and then position a manual control lever to condition the tape placement device for operation. When the end of the message just transmitted is sensed by an end of the message responsive mechanism, the tape placement device automatically feeds the new tape into transmitting position on the tape feed sprocket. During the period in which the change of tapes is taking place, blank feed out signals are automatically transmitted by a special transmitting cam while the transmitter is held inoperative. When the new tape assumes its transmitting position on the tape feeding sprocket, the transmitter resumes operation as before and effects the transmission of the new message. It is thus evident that an attendant may move from one transmitter to the other inserting tapes without waiting for the end of a message in any particular transmitter. In this way, traffic can be handled very efficiently with the lapsed time between messages reduced to a minimum, or more specifically to the short interval of time required to feed the new tape into transmitting position. Since blank feed out signals are transmitted to the other end of the line during this time to provide space between messages, and such space is necessary in order to readily distinguish one message from another, it is observable that there is no actual loss of time between messages.

An object of the present invention is to provide an automatic tape placement device for tape transmitters wherein a new message tape is automatically fed into transmitting position when a prior message tape has completed transmission of its message.

A further object of the invention is to provide

2

in a tape transmitter, an automatic tape placement device having manually operable conditioning means which conditions said device to feed a succeeding message tape into transmitting position when a prior message tape has completed transmission of its message.

Another object of the invention is to provide in an automatic tape transmitter, a tape placement device which functions to feed a new message tape into transmitting position when a prior message tape has completed transmission of its message and an auxiliary transmitting means which transmits space out signals while a change of tapes is taking place.

10 Other objects, features, and advantages of the invention, while not specifically recited above, will appear from the detailed description which follows when read in conjunction with the drawings wherein:

15 Fig. 1 is a partial elevational view of the transmitter, showing particularly portions of the tape placement device involved in the present invention;

20 Fig. 2 is a partial sectional view particularly emphasizing the relationship of the tape placement device to the transmitter proper;

25 Fig. 3 is a detailed view showing particularly the tape feeding finger which forms part of the present invention;

30 Fig. 4 is a detailed sectional view, illustrating particularly contact operating mechanisms involved in the present invention;

35 Fig. 5 is a diagram of the circuit arrangement used in the present invention; and

40 Fig. 6 is a detailed view of a tape guiding means utilized in the present invention.

The present invention is herein shown as particularly adapted for use with a tape transmitter such as is shown in the patent of M. T. Goetz, 2,296,845, dated September 29, 1942. It is understood, however, that the disclosure of the Goetz patent is modified in accordance with the present invention and that for details of the description of the transmitter itself reference should be had 45 to said patent.

In the drawings, numeral 11 represents a constantly rotating shaft which is suitably journaled on end walls 12 and 13 of the transmitter and is driven from a gear 14 as in a standard transmitter.

50 Shaft 11 carries a transmitting cam sleeve 17 (Fig. 2) which is releasable for continuous rotation by energization of a start clutch magnet 18 not shown in the mechanical part of the drawings but illustrated in the circuit diagram (Fig. 5).

55 The cam sleeve 17 permits the sequential operation

of a series of transmitting gooseneck levers 19 (only one of which is shown) which operate associated transmitting contacts 21 in accordance with the positions assumed by their individually allied tape sensing levers 22. In each rotation of cam sleeve 17, a signal code combination is transmitted and as is described in the Goetz patent, a bail 23 mounted on a common pivot 24 with sensing levers 22, withdraws pins 26 carried by the sensing levers 22 which in the previous transmitting cycle have sensed a perforation in tape 27. A tape stepping pawl (not shown) is then effective to step ratchet 28 carried by shaft 29 to advance tape feed sprocket 31 which is also carried by shaft 29 to the next position. This results in the advancement of a new row of perforations of tape 27 into transmitting position and bail 23 now allows the sensing levers 22 by means of their pins 26 to feel the tape for a new selection.

In accordance with the present invention there has been added to the constantly rotating shaft 11, a small pinion 33 which is in mesh with an idler gear 34. This latter gear, in turn, drives a gear 36 which is attached to a shaft 37 suitably journaled on the previously identified end walls 12 and 13. Fixedly secured to shaft 37 is a driving part 38 of a ratchet clutch indicated generally at 39. The driven part 41 of the clutch 39 is slidably mounted about the shaft 37 and in its rest position is held out of engagement with the driving part 38, by means of an extension 47 of a clutch throwout lever 42 as will immediately hereinafter appear. The clutch throwout lever 42 is pivoted at points 43 and includes pole pieces 44 which are operable under the control of a tape placement clutch magnet 46. When magnet 46 is pulsed, clutch throwout lever 42 pivots counterclockwise (Fig. 2) and thereby removes its extension 47 from engagement with cam surface 48 of a shoulder 49 which forms part of the driven part 41 of the clutch. Spring 51 now slides the driven part 41 of the clutch into engagement with the driving part 38 and a sleeve 52 mounted about shaft 37 and connected with the driving part of the clutch by notched connection 50 is now released for rotation. When clutch magnet 46 is de-energized, extension 47 of clutch throwout lever 42 will be placed in the path of cam surface 48 of shoulder 49 and the driven part of the clutch becomes automatically disengaged. It should be mentioned at this time that sleeve 52 rotates slower than the transmitting sleeve 17 and is designed to make only one revolution to six revolutions of the transmitting cam sleeve 17 for a purpose which will hereinafter appear.

Mounted on a cylinder 55 fixed to sleeve 52 is a segmented tape feed member 56 having a raised feeding segment 57 which is designed to engage tape 27 and press it against an idle pressure roller 58 as will later be described. Roller 58 is supported on bell crank 59 which is pivoted at 61 and urged in a clockwise direction (Fig. 2) by means of a spring 40. This enables a small arc of the pressure roller to protrude slightly through an aperture 62 of shelf 63 when bell crank 59 rests against a stop 60. To maintain the tape in exact alignment with the feed sprocket 31, a pair of tape guide discs 64 and 66 are mounted in any convenient manner at either side of the cylinder 55. The distance between guide discs 64 and 66 is just sufficient to accommodate a width of tape. Pivotally supported on a pin 67 extending into a cutout portion 45 of cylinder 55, is a tape feeding finger 68 which is normally urged in a counterclockwise (Fig. 2) direction by means of a suit-

ably mounted leaf spring 69. A shoulder 71 of finger 68 is shaped so as to receive the end of a new tape 27A which may be inserted while the previous tape 27 is transmitting its message. The leading end of tape 27A is at this time pressed against portion 73 of member 56 by shoulder 71 of finger 68.

When sleeve 52 is released for a single revolution as will later be described, newly inserted tape 27A is drawn forward by finger 68 and the feeding segment 57 of member 56 then presses the tape 27A against pressure roller 58 and thereby feeds the tape forward onto the feeding sprocket 31. For insuring that the tape will be properly directed towards the feeding sprocket 31, a flared guide 35 having a cutout portion 30 is provided. The cutout portion 30 furnishes clearance for segmented member 56 while its edges 25 act to deflect the tape towards feed sprocket 31. Segment 57 is just long enough to feed the first feed hole of the new tape onto the teeth of feed sprocket 31 in transmitting position. As will be later pointed out in the description, when a change of tapes is taking place, tape feed ratchet 28 and sprocket 31 are freely rotatable so as to facilitate the introduction of a new tape, the feed holes of which automatically find the pins of feed sprocket 31. After the finger 68 moves a short angular distance, a pin 74 carried thereby engages the high part of a fixed cam 76 which is suitably mounted about shaft 37. When this occurs, finger 68 is urged in a clockwise direction (Fig. 2) freeing the tape from its grasp and allowing the feed to take place solely under the control of segment 57 of member 56. As the finger 68 continues to rotate its pin 74 will again engage a low part of the fixed cam 76 and the finger will be returned to its original position.

Also carried on sleeve 52 is a transmitting cam 77 which is designed to send six blank signals with start-stop impulses to provide space between messages received at a remote point. To provide the start-stop impulses, cam 77 includes six lobes 78 and since sleeve 52 rotates only once for each six revolutions of transmitting sleeve 17, as already indicated, six blank feed out signals will be transmitted when sleeve 52 is released for a single revolution. This is accomplished by operation of follower 70 of cam 77 which is pivoted at 40 and controls the opening and closing of transmitting contact pair 75 associated with signal line 80.

With particular reference to Figs. 4 and 5, the conditioning of the tape placement device for operation in response to an end of message indication will now be given. When transmitting cam sleeve 17 is rotating, transmitting clutch magnet 18 is energized over the following circuit: From battery, through the winding of magnet 18, 60 through contact pair 81 (now closed), over lead 82 and through contacts 83 and 84 (now closed) to ground. The same ground circuit just described extends from lead 82, over lead 86 and through signal lamp 87, which is now illuminated, to battery. Signal lamp 87 indicates at this time that transmission is taking place in the normal manner with a tape being fed by sprocket 31.

When it is desired to condition the tape placement device for operation, the tape is inserted 70 on feeding finger 68 as explained, and a manual control lever 88 having a finger piece 90 is operated. This causes the latter lever to pivot counterclockwise (Fig. 5) about point 89 against the influence of spring 91. At this time, a lever 92 which is pivotally carried at 65 by lever 88, is

drawn to the left (Fig. 5) by its spring 93 and its upper end moves under and raises up a pivoted lever 54, resulting in the opening of a contact pair 94 and closure of a contact pair 96. Opening of contact pair 94 breaks an obvious circuit extending to signal lamp 97 which is now extinguished and thereby indicates that a new tape has been inserted into the transmitter and is ready for transmission when the previous message tape has been transmitted. Closure of contact pair 96 prepares a circuit for the tape placement clutch magnet 46 as follows: From battery, through closed contact pair 96, through the winding of the clutch magnet 46, over conductor 98 and through contacts 99 and 84 (when closed) to ground.

As described in the Goetz patent, when the end of a message being transmitted is reached, an end of message feeler 101 (Fig. 5) senses such a condition and pivots about point 102 in a clockwise direction. This frees a latch 103 to move about its pivot 106 under the impetus of spring 104. Pin 107 carried by latch 103 now moves against an end of message control lever 108, causing it to pivot counterclockwise and latch up at notch 110 of lever 109 which is pivoted at 111 and urged clockwise by a spring 112. As a result of the movement of lever 108, contacts 83, 84, open and contacts 84, 99 are closed. Opening of contacts 83, 84 breaks the circuit to transmitter clutch magnet 18 and extinguishes lamp 97. Closure of contacts 84, 99 completes the previously described circuit for the tape placement clutch magnet 46. Thus, at this time, cam sleeve 17 is stopped and sleeve 52 is released for a single revolution.

Sleeve 52 carries a cam 113, which after a partial rotation by means of a pin 114 moves against projection 116 of lever 92, removing the upper end of this lever from beneath lever 54 and allowing manual control lever 88 to assume its original position. At this time, contact pair 94 will again close, illuminating lamp 97, and contact pair 96 will reopen breaking the prepared circuit path for clutch magnet 46. Also carried on sleeve 52 is a cam 117 which is designed to operate a follower 118 pivoted at 119 and urged in a clockwise direction by spring 121. When cam sleeve 52 starts into rotation, follower 118 presses against a bar 122 (equivalent to manually operable bar 108 shown in the Goetz patent), to slide it downwardly so that a pin 123 carried thereby moves against lever 109 and thereby frees lever 108 from notch 110 for movement so that contacts 99, 84 open and contacts 83, 84 are closed. Opening of contacts 99, 84 causes a further break in the circuit for magnet 46 since the circuit is also broken upon opening of contact pair 94. This insures that the clutch throwout lever 42 will be in a position to stop cam sleeve 52 after a single revolution. Closure of contacts 83, 84 prepares a circuit for transmitting clutch magnet 18 which cannot be completed at this time due to the fact that extension 124 of bar 122 is held downwardly causing contact pair 81 to remain open. This insures that the clutch magnet 18 will be held unoperated until sleeve 52 completes a single revolution. After sleeve 52 has made a single revolution, it will stop and bar 122 will be moved upward by means of a spring 125 as cam 117 nears its rest position and presents a low part to projection 134 of lever 118. This closes contact pair 81 and therefore energizes clutch magnet 18 over its previously described circuit. The transmitter will now commence transmission from the new mes-

sage tape which was fed into transmitting position on feed sprocket 31 upon release of sleeve 52 as already explained. During rotation of sleeve 52, six blank feed out signals are transmitted by cam 77 as pointed out above. It will be understood that for a more complete understanding of the end of message sensing mechanism, reference may be had to the previously mentioned Goetz patent. It will be further understood that no positive feed out mechanism is provided for the message tape which has just been transmitted since at the end of a message, bar 122 will move down as described and free a detent (not shown) which engages ratchet 28, so that feed sprocket 31 is free to turn under the weight of the tape which thereby discharges itself from the feed sprocket. As has been mentioned before, bar 122 shown in the present invention is equivalent to bar 108 described in the Goetz patent.

Various changes and modifications may be made in the present invention without departing from the spirit and scope thereof.

What is claimed is:

25. 1. A telegraph transmitter including transmitting means, a main feeding means for feeding a message control form, an auxiliary feeding means for feeding a new message control form into transmitting position for advancement by said main feeding means, control form receiving means for receiving the leading edge of a new message control form and a feed member having a segment thereon to frictionally engage the new message control form for causing the advancement of a predetermined length thereof, means for conditioning said auxiliary feeding means for operation, an end of message responsive mechanism effective when the transmission of the message of a prior control form has been completed for disabling said main feeding means and said transmitting means and for rendering said auxiliary feeding means effective to feed the leading end of said new message control form by means of said segment on said feed member into transmitting position to facilitate the further advancement of said new message control form by said main feeding means, and means effective when said new message control form has reached the transmitting position for rendering said transmitting means and said main feeding means operative for transmission of the new message.

2. A telegraph transmitter including transmitting means, a main feeding means for feeding a message control form, an auxiliary feeding means including a form gripping means and a segmented feed member for advancing a new message control form into position for further advancement by said main feeding means, an end of message responsive mechanism effective when the transmission of the message of the prior control form has been completed for disabling said main feeding means and said transmitting means and rendering said auxiliary feeding means operative to feed the new message control form by means of said segmented member, means for releasing said form gripping means while said segmented member is advancing said new form into transmitting position for further advancement by said main feeding means and means effective when the new message form has reached transmitting position for rendering said transmitting means and said main feeding means operative for transmission of the new message.

75. 3. In a telegraph transmitter including means

for feeding and means for sensing a message control form, an auxiliary feeding means for advancing a new message control form into position for further advancement by said first mentioned feeding means, a gripper carried by said auxiliary feeding means for holding a leading end of a new message control form, a roller, a segmented portion on said auxiliary feeding means for cooperating with said roller to frictionally advance the new message control form into position for further advancement by said first mentioned feeding means, and means operable in response to the sensing by said control form sensing means of an end of message signal in a prior control form for actuating said auxiliary feeding means, said gripper releasing the leading end of the control form during the advancement thereof to said first mentioned feeding means by said segmented portion and roller.

4. In a telegraph transmitter including means for feeding and means for sensing a message control form, an auxiliary feeding means for advancing a new message control form into position for further advancement by said first mentioned feeding means, a gripper carried by said auxiliary feeding means for holding a leading end of

a new message control form, a roller, a segmented portion on said auxiliary feeding means for cooperating with said roller to frictionally advance the new message control form into position for further advancement by said first mentioned feeding means, means operable in response to the sensing by said control form sensing means of an end of message signal in a prior control form for actuating said auxiliary feeding means, and means operable during the advancement of said control form by said segmented portion and roller for causing said gripper to release the leading end of the new message control form.
